UNITED STATES PATENT OFFICE.

GEORGE WALTER TURNER, OF BROOKLYN, NEW YORK.

COLOR-PRINTING.

SPECIFICATION forming part of Letters Patent No. 433,967, dated August 12, 1890.

Application filed February 23, 1889. Serial No. 300,984. (No model.)

To all whom it may concern:

Be it known that I, GEORGE WALTER TURNER, a citizen of the United States, residing in Brooklyn, in the county of Kings and 5 State of New York, have invented certain new and useful Improvements in the Art of Color-Printing, fully described and represented in the following specification and the accompanying drawings, forming part of the 10 same.

This invention relates to that branch of the art of printing known as "color-printing," its object being to provide an improved method and means for printing in colors, by 15 which an impression in two or more colors may be taken upon paper or textile fabrics by one impression operation.

While this invention is of general application in color-printing, it is of especial value 20 as applied to book and newspaper work, in which the necessity for speed renders it desirable that but one impression operation should be made for printing the sheet, and that the mechanism by which the result of 25 printing in colors is attained shall be as simple as possible. In the make-up of matter and other operations of making ready for printing modern newspapers the utmost dispatch is required, and although the desirability of being able to give that prominence to a particular subject which would result 30 from printing in different colors is apparent and has long been recognized, the usual means for accomplishing this end are so complex as to render them unavailable for use in 35 newspaper work. By my invention I am able to provide means which can be readily applied to existing printing-machines, and so expeditiously as to enable it to be used in the

40 printing of daily newspapers, and I attain this object by preparing a printing form or plate having surfaces of different heights, the picture or other matter which is to receive the color different from the body of the paper 45 being placed, preferably, slightly below the surface or plane of the main portion of the form or plate, so that the primary inking-rollers or other inking device will ink only the body or higher portions of the form or 50 plate without coming in contact with or inking the lower portions. These lower portions are inked, preferably by a secondary inking-

roller or other suitable device carrying the desired color and of the proper dimensions, and so constructed as to ink only the lower 55 portions of the form or plate. With this printing form or plate I use an impression-surface having corresponding faces of different heights arranged reversely to those of the printing form or plate, the higher portions of 60 the impression-surface being constructed of dimensions corresponding to those of the lower surfaces of the printing form or plate. The raised portions of the impression-surface are formed, preferably, by an extra overlay of 65 a form and dimensions corresponding with those of the lower printing-surfaces, and the paper or other material to be acted upon is fed in the usual manner, the impression being given by bringing the impression-surface 70 into printing contact with both the upper and lower printing-surfaces by one impression operation.

Although it is evident that my invention is especially adapted for use in that class of 75 printing-machines known as "web-presses," it is also applicable to any other class of printing-machines, whether using a curved or flat printing-surface, as will hereinafter appear.

For a full understanding of my invention a detailed description of mechanism embodying the same will now be given, reference being had to the accompanying drawings, forming a part of my specification, in which— 85

Figure 1 is a sectional elevation of one form of mechanism embodying my invention as applied to a web-printing machine. Fig. 2 is a plan of Fig. 1, certain portions of the printing and inking mechanism being broken 90 away to better illustrate my invention. Fig. 3 is a plan view of the type and impression cylinders of Fig. 1, but in a slightly-changed position. Fig. 4 is a perspective view, partly in section, of a flat printing-form made up according to my invention. Fig. 5 is a cross-section of the impression-surface for printing from a flat form. Fig. 6 is a cross-section of a flat form corresponding to the impression-surface of Fig. 3. Fig. 7 shows in perspective a modification of my invention, using three printing-surfaces of different heights. 95

Referring now especially to Figs. 1 to 3, H is the form or type cylinder of a web-print-

ing machine; I, the impression-cylinder; J, a portion of a second impression-cylinder, and K distributing and form rollers of the primary inking mechanism of the usual construction.

O is a stereotype-plate secured to the type-cylinder H in the usual manner, and provided, as shown clearly in Figs. 1 and 3, with a portion A, depressed below the body or main portion B of the plate.

The impression-cylinder I is provided with an overlay C, of any suitable material, secured to the blanket R by the use of cement, thread, or in any other suitable manner, this overlay being of a size corresponding to the depressed portion A of the stereotype-plate, and placed in such relative position thereto as to insure its impression therewith as the cylinders revolve. Only one depressed portion on the type-cylinder and one overlay on the impression-cylinder are shown, as this is sufficient to illustrate my invention; but it will be understood that the number and form of these corresponding raised and depressed portions will be varied as desired, in accordance with the result to be attained.

For the purpose of inking the depressed portion A of the stereotype-plate I provide a secondary inking mechanism, as follows: The cylinder L is geared to the type-cylinder H, so as to rotate in unison therewith, and is provided upon its face with an inking-pad P, corresponding in size and shape to the surface A, the cylinder L being so timed in its movement that the pad P registers with the surface A of the stereotype-plate as the cylinders L and H revolve. This inking-pad P is inked by means of the inking-roll M, receiving ink from the roll N, which may be supplied with ink by any of the usual methods, or covered with porous material and charged with ink. The cylinders and rolls are geared by means of gears a, b, c, d, and e, as shown in dotted lines in Fig. 1, so as to rotate in proper relative time, and the cylinder L, as shown in Fig. 2, is made adjustable, so as to secure the accurate registry of the pad P with the lower surface A of the stereotype-plate.

The operation of the mechanism described is as follows: The paper T is led from the web-roll over the impression-cylinder I and between it and the type-cylinder H, and thence around the perfecting impression-cylinder J, as shown by the arrows in Fig. 1. The body of the type-cylinder H is inked by the main inking mechanism K, the surface A of the stereotype-plate receiving no ink therefrom on account of its position below the surface B of the body of the stereotype-plate. The pad P on the cylinder L is supplied from rolls M N with ink of a color different from that of the main inking mechanism K, and by the revolution of the cylinder L inks the depressed surface A, but its size and shape corresponding thereto inks no portion of the body of the stereotype-plate. As the type

and impression cylinders H I revolve and the impression is taken, the part of the paper which is opposite the overlay C is brought into printing contact with the lower surface A of the stereotype-plate and receives an impression therefrom in ink of a different color from that of the body of the paper, the result of the operation described being a product consisting of a web or sheet of paper printed in two colors and thus printed by one impression operation.

The inking mechanism shown and described is that which I prefer to use; but it is evident that any other form of inking device may be employed whereby the upper and lower portions of the stereotype-plate will be inked in different colors.

In Figs. 4, 5, and 6 I have shown my invention applied to a flat form. Fig. 4 shows clearly a construction in which the surface A, containing the illustration or other matter which is to be printed in a different color, is depressed below the surface of the body B of the type form or plate. Figs. 5 and 6 show in cross-section a corresponding flat impression-surface and type-form in carrying out my invention. As shown in Fig. 5, the overlay C of the impression-surface is backed up by additional paper D or other material. For the purpose of preventing an abrupt bend in the paper when the impression is taken, the edges of the overlay C are preferably beveled, as shown at E in Fig. 5. It has also been found advisable to make the overlay C of sufficient thickness to insure its contact with the surface A slightly in advance of that of the main portion of the impression-surface with printing-surfaces B.

In Fig. 7 I have shown a modification of my invention, in which printing-surfaces of three different elevations are used, a third printing-surface A' being shown inside the surface A. In printing from a form of this character a third inking-pad will be used for inking the surface A', as will readily be understood. It will also be understood that instead of the surface A' being below the surface A and supplied with a different color, this surface may be level with the surface B, so that an impression in the same color as the body of the paper will be taken within the matter printed in a different color by the depressed surface A, and it will be understood that with either a flat or curved form or plate the form and size of the depressed portion may be varied in any manner desired.

I have discovered that the depression necessary to avoid contact of the lower surface or surfaces with the primary inking mechanism and to insure its or their engagement with the corresponding projecting face or faces of the overlay or raised portion or portions of the impression-cylinder for printing-contact is so slight as to cause no injurious or undesirable effect upon the paper in printing it.

Instead of the printing surface or portion

A being depressed, it may be raised above the body or main printing-surface of the type-cylinder sufficiently to permit its being inked in one color by ordinary inking mechanism, 5 which will not ink such main surface. The latter in such case may be inked by an inking-cylinder of such diameter that one revolution of it will ink said main surface, a portion of its face being cut away or de- 10 pressed to clear the raised portion A without inking it. In such case also, instead of the impression-cylinder having a raised face, it will be provided with a depressed face corresponding in shape with the raised portion A, 15 and so as to properly press the paper against such raised portion.

Various other modifications may be made in the apparatus for carrying out my invention by persons skilled in the art without departing from my invention.

I am aware that printing forms or surfaces have been made up in sections, and so that one or more of them may be so moved as to stand above the level of the other sections 25 temporarily and for the purpose of taking ink, each section taking a different color, after which the different sections are brought to a common level for the impression; but in such constructions each impression is taken 30 only from those sections which are relatively on a common printing level.

What I claim is—

1. The method of printing in colors, which consists in taking an impression from printing-surfaces of different heights, which have been inked in different colors, by one impression operation, substantially as described.

2. The method of printing in colors, which consists in taking an impression from printing-surfaces of different heights, which have been inked in different colors, by bringing into impression contact with said surfaces by one impression operation an impression-surface having corresponding portions of different heights, substantially as described.

3. The method of printing in colors, which consists in preparing a printing form or plate having surfaces of different heights, inking said surfaces in different colors, and taking an impression from said surfaces by one impression operation, substantially as described.

4. The method of printing in colors, which consists in preparing a printing form or plate having surfaces of different heights, and an impression-surface having corresponding portions of different heights, inking said printing-surfaces in different colors, and taking an impression by said printing and impression surfaces at one impression operation, substantially as described. 55

5. The combination of a printing form or plate having surfaces of different heights, means for inking the same in different colors, and means for taking an impression from said surfaces by one impression operation, substantially as described. 60

6. A printing form or plate having surfaces of different heights, in combination with means for inking the same in different colors, and a coacting impression-surface having corresponding portions of different heights, whereby an impression is taken from both lower and upper printing-surfaces by one impression operation, substantially as described. 70

7. The combination, with a printing form or plate having relatively fixed surfaces of different heights, of an inking mechanism whereby the upper surfaces only are inked and a second inking mechanism whereby the lower surfaces only are inked, substantially as described. 75

8. The combination of a printing form or plate having relatively fixed surfaces of different heights, independent inking mechanisms, whereby said surfaces are inked in different colors, and a coacting impression-surface adapted to act upon both the upper and lower printing-surfaces at one impression operation, substantially as described. 85

9. A printing form or plate having relatively fixed surfaces of different heights, in combination with an inking mechanism whereby the lower surfaces only are inked, substantially as described. 90
